COMBINED CIGARETTE CASE AND
LIGHTER

Leo A. Denit, Salem, Va.

Application March 13, 1934, Serial No. 715,342

3 Claims. (Cl. 206—41.4)

This invention relates to an improvement in combined cigarette cases and lighters of the character wherein a pyrophorous lighter is applied to a cigarette-case.

The object of the invention is to have a package of cigarettes and a lighter for the cigarettes in one combined casing or structure, convenient for use, and to eliminate the separate carrying of cigarettes and a lighter or matches, which would make it necessary to reach in the pockets first for the cigarettes and thereafter for the lighter or matches. By combining these in one casing, they are conveniently and compactly carried so as to be accessible together for instant use. It is well-known that by enclosing the cigarettes in a relatively tight casing, such as a metal case, they keep fresh longer than otherwise, and, since the package of cigarettes is usually wrapped in a "cellophane" wrapper, it is desirable to insert the complete package in the casing so that the cigarettes will not be disturbed therein.

This invention is shown applied to a case capable of receiving the complete package of cigarettes, and combines therewith in the same structure a lighter for the cigarettes.

In the accompanying drawing:

Fig. 1 is a perspective view of the combined cigarette-case and lighter with the top of the cigarette-case removed;

Fig. 2 is a detail perspective view of a portion of the casing showing the lighter in position to be inserted therein;

Fig. 3 is a bottom plan view of the complete casing;

Fig. 4 is a vertical section through the complete casing;

Fig. 5 is a horizontal sectional view on the line 5—5 of Fig. 4; and

Fig. 6 is a plan view of a modified form of lighter.

The invention is shown applied to a conventional form of cigarette case, the body portion of which is designated 1, and has a telescoping top 2 capable of fitting over a package of cigarettes encased within the body portion 1, although the invention may be applied to other forms of cigarette-cases, such, for instance, as having the top hinged or otherwise secured to the body portion. The lighter structure is shown as applied to the bottom of the cigarette-case, although it will be obvious that it may be applied to a side or to the top thereof, but its application to the bottom arranges the lighter in a convenient place for use.

The lighter structure has a casing 3 rigidly fixed to, or integral with, the cigarette-case, such

as the body portion 1 thereof, and preferably is of the same shape and area as the bottom of said case when the lighter is applied to the bottom thereof. The lighter casing 3 has an opening 4 therein, which is open to one end of the casing 3 in position to permit a lighter to be inserted into the opening; and, to facilitate the removal of the lighter, one side of the casing 3 has a thumb-notch 5 therein, as shown in Figs. 2 and 3.

The lighter preferably is of the pyrophorous type, and to facilitate compactness it is relatively flat, as shown in Fig. 2, wherein its casing is designated 6, and is shaped to approximately fit the opening or chamber 4 in the lighter casing 3. The casing 6 normally is held in the lighter casing 3, by a slight punch-press 7 in a side thereof in position to enter a corresponding indentation in a side of the lighter casing 3. To permit removal of the lighter from the lighter casing, the lighter has thumb-grooves 8 in opposite sides thereof at one end to facilitate grasping of the lighter with a finger-nail in the thumb-notch 5 for removing the lighter from the lighter casing.

The casing 6 of the lighter may be made of transparent material, if desired, in order to permit inspection of the contents, as, for instance, to see when the lighter fluid has become exhausted, or, instead of making the casing 6 of transparent material, a window 9 may be formed in a side thereof for inspection of the contents.

The casing 6 contains the usual lighter fluid capable of ignition, and to make the fluid available for use a wick 10 extends thereto, and through a sleeve 11 threaded into an end of the lighter (as shown in Figs. 2 and 5). A steel pin 12 is inserted into the end of the casing 6 beside the wick 10.

When the lighter is in place in the chamber 4, leakage of fluid is prevented by absorbent material, such as cotton 13, which is placed in one end of the chamber 4, against which the end of the wick would press so as to keep any fuel from running out of the chamber 4 and getting onto the clothes of the person carrying the lighter and cigarette-case.

As shown in Fig. 3, a bar 14 of a suitable spark-giving alloy, such as cerium iron alloy, is fitted and secured in a groove 15 formed in the bottom of the lighter casing 3, so that the lighter may be removed from the casing and the wick ignited by rubbing the steel pin 12 along the surface of bar 14, which creates a spark sufficient to ignite the fuel-saturated wick.

This arrangement enables a person to remove

- a cigarette from a case, and then by turning the case upside down to remove the lighter from its casing and obtain a flame on the wick 10 merely by rubbing the steel pin 12 along the surface of the bar 14, which creates a spark sufficient to ignite the wick. This makes it unnecessary to hold the lighter usually employed and rotate the small wheel for creating the spark which ignites the wick.
10. However, instead of using the type of lighter shown in Figs. 1 to 5, the form shown in Fig. 6 may be employed wherein the spark is created by rotating a wheel 16 in contact with a flint pressed thereagainst in the usual way. The 15 shape and structure of the lighter shown in Fig. 6 is otherwise similar to that shown in Figs. 2 to 5, such as described above, except that the flint and wheel are substituted for the striking pin 12.

I claim:

20. 1. In a structure of the character described, the combination of a casing having a chamber therein adapted to receive a lighter, said chamber being open to a side of the casing, a lighter insertable through the open end of the chamber into the casing and removably disposed therein, said lighter having a wick and pin arranged adjacent each other, and a bar of spark-giving material secured to the exterior of the casing and adapted to ignite the wick upon removal of

the lighter from the casing and rubbing the pin longitudinally of the bar.

2. In a device of the character described, the combination of a casing having a chamber therein open at a side of the casing, a pyrophorus lighter 5 removably inserted into the chamber through the open side thereof and removable from the chamber, said lighter having a body portion adapted to contain a hydrocarbon fluid, said body portion having a sleeve threaded in an end thereof with a 10 wick extending through the sleeve and having one end inserted into the fluid and the other end of the wick being arranged at the outer end of the sleeve, and a pin fitted in the end of the body portion at one side of the sleeve, and a bar of 15 spark-giving material secured to the casing on the outside thereof and adapted to ignite the wick when the pin is rubbed lengthwise of said bar.

3. In a lighter structure of the character described, a casing having a chamber therein open 20 at one end to the outside of the casing, one side of said casing having a thumb-notch therein at the open end of the chamber, and a lighter removably inserted into the chamber through the open end and having a thumb-groove in a side thereof 25 facing the thumb-notch and accessible therethrough for removal of the lighter from the casing.
